UNITED STATES PATENT OFFICE.

DONALD NOBLE, OF BRIDGEPORT, CONNECTICUT.

MACHINE FOR COVERING OR INSULATING WIRE WITH YARN OR ITS EQUIVALENT.

1,032,854.

Specification of Letters Patent. Patented July 16, 1912.

Application filed August 3, 1911. Serial No. 642,163.

To all whom it may concern:

Be it known that I, DONALD NOBLE, a subject of King George V, King of Great Britain, residing in the city of Bridgeport, county of Fairfield, State of Connecticut, United States of America, have invented certain new and useful Improvements in Machines for Covering or Insulating Wire with Yarn or Its Equivalent; and I do declare the following to be a full, clear, and exact description of the invention, such as will enable others skilled in the art to which it appertains to make and use the same.

My invention relates to machines for covering or insulating wire with yarn or its equivalent, and has for its objects to provide a tension device which shall be operative against the yarn cop at comparatively low speeds of the spinning head but which shall be withdrawn entirely from said cop at comparatively high speeds of said head.

My present improvement is applicable to the machine shown and described in Letters Patent of the United States, No. 1,000,109, issued to me August 8, 1911, and I have therefore illustrated and will briefly refer to herein certain parts of said machine that are covered by the claims of said application, although I wish it to be understood that I limit my present claims to the particular tension devices which I have illustrated herein and will hereinafter describe.

In my pending application aforesaid I illustrated and briefly described certain means for exerting an automatically diminishing tension against the yarn cop, which means comprises a spring controlled tension finger carried by the spinning head and constantly bearing against a bushing which carried the yarn cop, but I have ascertained that such a tension either against the cop itself or against any element directly associated therewith was detrimental when the spinning head was revolving at a high rate of speed because the yarn was very apt to break. I have further ascertained that the normal slipping frictional contact which exists between the spinning head and the yarn cop or any element which carries the latter, is not only sufficient when the yarn is withdrawn from the cop at comparatively high speeds of the spinning head, but that such tension greatly militates in favor of uniform tension which the auxiliary rolls referred to in said application exert against the yarn as

the latter is delivered to the covering devices.

It is the especial object of the present invention to provide a tension against the yarn cop or an element carrying the same, by utilizing the principle of centrifugal force, which principle is predominantly present in a high speeded machine like the one under consideration.

Referring to the accompanying drawing Figure 1 is a longitudinal sectional elevation of a spinning head constructed in accordance with my present improvement. Fig. 2 a section at the line *a*, *a*, of Fig. 1. Fig. 3 a detail perspective view of the detachable head of the main shaft. Fig. 4 a detail perspective view of the tension sleeve. Fig. 5 a section at the line *b*, *b*, of Fig. 1. Fig. 6 a plan view of my improved spinning head, and Fig. 7 a section at the line *c*, *c*, of Fig. 6.

Similar numerals of reference denote like parts in the several figures of the drawing.

1 is a hollow power shaft, and 2 is the spinning head which has an elongated internal hollow hub 3.

4 is a detachable head which has a shank 5 that extends within the forward end of the shaft 1, and 6 is a set screw which is driven through the hub 3 and shaft 1 against the shank 5 whereby it will be readily understood that said shank, shaft and hub are rigidly secured together as to rotation. This shank 5 has an opening 7 extending therethrough and leading into the hollow shaft, 80 and within this opening the spinning quill 8 is secured by means of set screw 9 driven through the head against said quill, the latter being provided throughout its length with an open slot 10 which leads into the opening 7 and through which the wire 42 to be covered is led.

The head 4 is cut away to form small recesses 11, 12, which are in pairs that are disposed in planes at right angles to each other on opposite sides of the axial center of said head, for the purpose presently to be explained.

13 is a bushing which surrounds the hub 3 and is sufficiently tight thereon so that it may be revolved independent of said hub but with a certain predetermined frictional contact therewith. The yarn cop 14 is carried by a cop tube 15 which latter is forced over the bushing 13 the latter being pro-

vided with ribs 16 so that the tube will fit over the bushing fairly tight. The rear extremity of the bushing 13 is preferably flanged as seen at 17 and this flanged portion bears against any suitable washer 18 contained within the head 2, but no portion of the cop or cop tube is in contact with the spinning head as in the instance of my application above referred to.

10 In drawing the yarn from the cop, without any tension acting thereagainst except that provided by contact between the hub 3 and bushing 13, there is no likelihood of the yarn breaking when the spinning head is revolved at a comparatively high rate of speed, and such a tension is not only ample but exceedingly desirable in connection with the auxiliary tension rolls 19, described in my said application, around which the yarn 20 is wound and from which said yarn is delivered directly to the covering devices.

A tension device which exerts a constantly decreasing pressure against the cop as the latter decreases in size means a tension that 25 is not uniform, and therefore when such a tension is employed the friction between the rolls 19 and the yarn cannot be uniform, and therefore the grip of the yarn on these rolls is at times too great and at times too little, 30 the consequence being that the yarn will sometimes break while at other times the tension exerted by such rolls is useless. Before entering into any description of my improvements I will briefly refer to these 35 rolls 19 and the parts that are associated therewith, although these elements have nothing to do with my present invention, and I refer to them merely to give a clearer understanding of the operation of the machine as equipped with my improvements.

20 is the rim of the spinning head which incloses the cop and also extends rearward of the head and within said rim and secured to the rear of the head 2 is a casing 21 45 through which the shaft 1 freely extends.

22 is a worm supported loosely by the shaft 1 and extending within the casing 21 and provided with a sleeve extension 23 which forms the journal bearing for the 50 shaft and which is secured to the bed 24 of the machine by means of set screw 25, so that it will be clear that said worm is a stationary element.

26 are spindles which are journaled with 55 in suitably disposed housings 27 in the casting 21, and 28 are worm wheels secured to the inner ends of these spindles and meshing with the worm 22, the yarn delivery rolls 19 being secured to the outer ends of these 60 spindles and extending through the rim 20, all arranged and operating as set forth in my pending application above referred to.

The yarn 49 is led from the cop and connected with the rolls 19 precisely in the manner described in my pending application

aforesaid, and all the conditions which characterize the mechanisms set forth in said application exist in the present construction with the exception of my improved ironer and polisher and tension devices hereinbefore mentioned, and therefore I will confine all further description to the mechanisms and devices that are immediately associated with my present invention.

30 is my improved tension sleeve which is assembled loosely around the hub 3 so as to have a free longitudinal movement, which sleeve is surrounded by a coil spring 31 that is confined between a flange 32 at the rear of the sleeve and a shoulder 33 of the head 4, the function of this spring being to normally drive the flange 32 against the outer edge of the bushing 13 so as to normally exert a considerable friction against said bushing to prevent the latter from readily turning on the hub 3, thereby rendering it more difficult to withdraw the yarn from the cop 14. This sleeve is constructed in the manner particularly shown at Fig. 4 with narrow diametrically opposite finger extensions 34 which fit and extend within the recesses 11 in the head 4, said fingers extending beyond the main body of the head and being connected by means of a cross plate 35 which is perforated at 36 to admit the quill 8.

Immediately in the rear of the plate 35 between the latter and the body of the head is a space 37 and depending within this space and immediately in the rear of said plate are tails 38 which extend from dogs 39 that are pivoted near their rear ends within the recesses 12, and it will be readily understood that if the forward ends of these dogs are spread, these tails will act against the plate 35 to withdraw the flange 32 from contact with the bushing 13. When the spinning head is revolved at a comparatively high rate of speed the centrifugal force will cause the outer ends of these dogs 39 to diverge, and will thereby relieve the cop from all tension save that which exists by frictional contact between the bushing and the hub 3, and when the speed of the head 2 slackens down to a predetermined rate, the spring 31 will force the flange 32 against the bushing 13 and thereby impose additional tension on the yarn cop. The

rate of speed of the spinning head, necessary to cause the outer ends of the dogs 39 to diverge by centrifugal force, or to cause the spring 31 to maintain the additional tension against the yarn cop, can be readily determined, and may be varied according to the size of the wire or the strength of the covering yarn, and the spring 31 may be more or less powerful as the occasion may demand, these being matters of experiment merely and fully within the range of ordinary mechanical skill.

The device which I have illustrated for ironing and polishing the covered wire comprises an anvil 40 secured to the quill 8 and a finger 41 pivoted to said anvil and having its rear extension beyond the pivotal point heavier than the front extension forward of said point. The forward portion of the anvil and finger are adapted closely to each other so as to firmly embrace the covered wire as it passes between them from the quill, and when the spinning head is revolving at a comparatively high rate of speed the rear extension of the finger 41 will be thrown outwardly thereby causing the forward part of the finger to be depressed firmly against the covered wire, whereby, in conjunction with the stationary anvil, said wire will be ironed and polished as fast as it is delivered from the quill.

But this form of ironing and polishing device has of course nothing whatever to do with the tension exerted against the cop, and I have merely illustrated and briefly described the same as exemplifying one form of such device which may be employed.

Having thus described my invention what I claim as new and desire to secure by Letters Patent is:—

1. In a machine for covering or insulating wire with yarn or its equivalent, the combination of the spinning head which carries the yarn cop, with a tension device carried by said head and adapted to have a normally yielding pressure against said cop at comparatively low speeds of said head, and centrifugally operated means for withdrawing said device from said cop when said head is revolved at comparatively high speeds.
2. In a machine for covering or insulating wire with yarn or its equivalent, the combination of the spinning head which carries the yarn cop, with a tension device carried by said head, a spring element for

causing said device to normally act against 45 said cop, and centrifugally operated means for withdrawing said device from the cop.

3. In a machine for covering or insulating wire with yarn or its equivalent, the combination of the spinning head, the yarn 50 cop carried by said head with a fixed slipping frictional contact, a spring actuated tension device adapted to normally act against said cop, and centrifugally operated means connected with said device for withdrawing the latter from said cop when the spinning head is revolved beyond a prescribed rate of speed.

4. In a machine for covering or insulating wire with yarn or its equivalent, the 60 combination of the spinning head, the yarn cop carried by said head with a uniform slipping frictional contact therewith, a tension sleeve slidably carried by said head, a spring which normally forces said sleeve against the cop, and means carried by said head and connected with said sleeve and operated by centrifugal force for withdrawing the sleeve from the cop when the head is revolved beyond a prescribed rate of 70 speed.

5. In a machine for covering or insulating wire with yarn or its equivalent, the combination of the spinning head which carries the yarn cop, with a tension device, a 75 spring for causing said device to act against the cop when the head is revolving at comparatively low speeds and centrifugally operated means for causing said device to be withdrawn entirely from said cop when the head is revolving at comparatively high speeds.

In testimony whereof I affix my signature in presence of two witnesses.

DONALD NOBLE.
